UNITED STATES PATENT OFFICE

LOUIS E. DRUMMOND, OF UPPER DARBY, PENNSYLVANIA

APPARATUS FOR TRANSFUSION OF BLOOD

Application filed April 9, 1931. Serial No. 528,785.

Objects of the present invention are to facilitate and improve the transfusion of blood from the donor to the patient, to preclude all possibility of a reversal of flow from 5 in the direction of from the donor to the patient, to accurately and automatically measure and record the quantity of blood transfused, to guard against accidental interruption of the flow, and to provide for 10 convenience in cleaning the apparatus employed.

Generally stated, the invention consists of a pump having detent or locking and unlocking devices which compel its hand operated piston to be normally operated through full length strokes and then only when the pump valve is put by the piston in proper position for intake from the donor and for outlet to the patient and which permit the 20 piston to be operated for intermediate and full length strokes, on occasion, for the intake and expulsion of cleaning fluid, only when the pump valve is put by the piston in proper position to cut out both the donor and patient and connect the fluid, the pump also having an integrating indicator responsive to full piston strokes delivering blood to the patient, and the apparatus as a whole being capable of ready disassembly for 30 cleaning and assembly for use.

The invention also comprises the improvements to be presently described and finally claimed.

In the following description reference will 35 be made to the accompanying drawings forming part hereof and in which

Figure 1 is a top or plan view with parts broken away.

Fig. 2 is a side view.

40 Figs. 3, 4 and 5 are transverse sectional views taken respectively on the lines 3—3, 4—4, and 5—5 of Fig. 2.

Fig. 6 is a view similar to Fig. 4 showing the parts in another position.

45 Fig. 7 is a view partly in elevation and partly in section and referred to in connection with the following description of the disassembly of the parts.

In the drawings 1 is a fixed frame and it 50 may well be provided with a clamp 2 for de-

tachably securing it to an appropriate support. There is a three-way valve plug 3 operatively immovable on the fixed frame. As shown it projects from a standard 4 forming part of the fixed frame. There is a cylinder 5 operatively fixed on the frame 1 and it may well be made of glass and marked with a scale indicating its position in respect to the piston and in that way the contents of the cylinder. The cylinder 5 is shown as carried by a stand- 55 ard or support 6 attached to the frame 1. There is a port 7 from the cylinder to the plug 3 of the valve. 8 generally indicates a frame mounted for limited oscillation on the fixed frame. As shown it is pivoted on the 60 supports 4 and 6, and its oscillating movement is limited by contact with stop 9 provided on the support 6. There is a three-way valve casing 10 forming part of the oscillating frame, and it is provided with three openings for cooperation respectively with three openings in the plug valve 3. There is a third frame, generally indicated at 11, and it has a handle 12. This third frame is recipro- 65 catably mounted on the second frame and is 70 provided with a plunger 13 for the cylinder 5. There is mechanism interposed between the fixed frame 1 and the other two frames 8 and 11, and it is adapted to permit endwise motion in two directions of the third frame 11 75 75 in middle position thereof shown in Fig. 4, and to afford endwise motion thereof only in one direction in each of the two limiting positions thereof of which one is indicated in Fig. 6. This mechanism comprises a toothed rack 80 85 14 on the frame 1, and a yoke 15 on the reciprocating frame. This yoke is provided at its intermediate portion with a notch 16 through which the rack 14 may freely pass. The yoke 15 is also provided with two other 90 notches 17 and 18. At the notch 18 is ar- ranged a pawl 19. Upon inward motion of the handle 12 the rack 14 passes freely through the notch 18, and the detent 19 pre- 95 vents any possibility of movement of the han- dle 12 outward. The notch 17 is fitted with a detent 20 and upon completion of the in- 100 ward stroke of the handle and not before, the frame 11 can be turned to align the notch 17 with the rack and then the handle can

be moved freely outward but only for a full stroke. It will be understood that the frame 11 can be turned only when the yoke is clear of the ends of the rack. In this way since the 5 piston makes full strokes only, the quantity of blood transfused at each stroke is the same and is known.

There is an integrating mechanism interposed between the fixed frame 1 and the third 10 frame 11, and it is actuated by the movements of the third frame 11 in inward direction only, which is the direction of transmitting blood to the patient, previously taken from the donor. As shown this mechanism 15 comprises a rotating graduated and numbered disk 21 provided with ratchet teeth 22, and these teeth are engaged by a pawl 23 actuated through a post 24 by a cam 25 on the sliding frame 11 when the latter is moved inwards.

The mode of operation may be described as follows:

The nozzle 26 is connected by proper means with the patient. The nozzle 27 is likewise 25 connected with the donor, and the nozzle 28 is connected with a supply of cleaning fluid. With the parts in the positions shown, the oscillating frame 8 is turned in the position opposite to that shown in Fig. 6. This connects the bore 7, Fig. 7, through the openings 29 and 30, Fig. 5, with the nozzle 26. The handle 12 is pulled out carrying with it the plunger 13 and drawing a cylinder full 30 or measured quantity of blood from the donor. The outward stroke must be completed in order to get the yoke 15 clear of the rack so that the frame 8 can be turned, and the detent 20 prevents all retrograde movement of the handle. Upon completion 35 of the out stroke, the frame 8 is turned into the position shown in Fig. 6. This disconnects the donor and connects the patient by way of the port 7 and the passages 30^a and 31, Fig. 5. The handle 12 is then pushed in and the instroke is a full stroke by reason of 40 the action of the detent 19. Thus the cylinder full of blood is injected into the patient. On the instroke the cam 25, operating on the post 24, actuates the disk 21 and indicates that 45 one cylinder full of blood has been transfused. By repetition and observation the required quantity of blood can be transferred. By turning the frame 8 into middle position, 50 at the end of a stroke in either direction, both the patient and donor are cut out and the passage 7, Fig. 7, is connected by passages 34 and 35, Fig. 5, with the nozzle 28, and in that 55 position the piston can be worked freely in either direction because the notch 16 is not provided with a detent. In this way coagulated blood, if any, can be washed from the cylinder and then the transfusion operation 60 can be renewed or continued.

65 The provisions for cleaning all parts of

the apparatus which are exposed to blood will now be described.

The valve casing 10 is turnably mounted on the plug 3 and is pressed by a spring 39, mounted on an extension 40 of the plug. 42 70 and 43 are collars at the ends of the spring, and 44 is a turnable catch which permits of the removal of the spring and valve casing 10. The valve casing is connected with the turnable frame 8 by the nozzles 27 and 26 which 75 take into forks 45 on the frame, so that the valve casing can be removed, and when returned to place is properly positioned.

The plug 3 is secured to the support 4 by a thumb nut 46 engaging a threaded stem 47 80 on the plug 3 and also the face of the support 4.

After the spring 39 and valve casing 10 have been removed by releasing the latch 44, the valve casing and nozzles can be washed. 85 The yoke at 11 is pivoted on the sleeve 45^a of the sliding frame and has a notch which engages the sleeve 46^a and may be clamped and released by means of the set screw 47^a. 90 The sleeves 45^a and 46^a slide on rods 48 and 49 on the oscillating frame 8. The yoke at 11 is provided with a claw 50 pivoted at 51 and provided with a set screw 52. The claw 50 detachably engages a button 53 on the piston rod. 95 By these means the piston rod is freed, and can be drawn by the button 53 out of the open end of the cylinder 5 towards the left in Fig. 2, for washing or cleaning. The cylinder is turned slightly and the detachable coupling or bayonet joint 54 is uncoupled, so 100 that the cylinder can be withdrawn toward the left in Fig. 2 through the opening in the support 6 and washed or cleaned.

The nut 46 is removed and the plug 3 can be withdrawn toward the right in Fig. 2. 105 Its extension passes through a hole in the support 4. Thus the plug can be cleaned. The pin 55 on the plug, Fig. 7, enters a hole in the support 4, Fig. 3, and serves to position the plug. The parts are assembled by a reversal of the described operations.

It will be obvious to those skilled in the art to which the invention relates that modifications may be made in details of construction and arrangement and matters of mere form without departing from the spirit of the invention which is not limited to such matters or otherwise than the prior art and the appended claims may require.

I claim:

1. Apparatus for transfusion of blood comprising, in combination, a pump having a single cylinder and having a piston and piston handle, a pump valve connected with and operated by rotary movement of the piston and adapted to be positioned for intake from the donor and for outlet to the patient and to cut out both patient and donor and to connect a supply of cleaning fluid locking and unlocking devices which compel the piston to be 130

operated through full length strokes when the pump valve is in proper position for intake from the donor and for outlet to the patient and which permit the piston to be operated for strokes of any length when the valve is in position to cut out both donor and patient and to connect a supply of cleaning fluid, and an integrating mechanism responsive to full piston delivery strokes to the patient.

2. Apparatus for transfusion of blood comprising, in combination, a fixed frame, a three way valve plug and a cylinder having communication with the plug and both mounted on the fixed frame, an oscillating frame mounted for limited oscillation on the fixed frame and having a valve casing provided with three outlets, a reciprocating frame reciprocatingly mounted on the second frame and having a handle and a plunger for said cylinder, locking and unlocking detent mechanism interposed between the fixed frame and the other two frames and adapted to permit free reciprocation of the reciprocating frame in middle position of the oscillating frame and to afford full stroke reciprocation thereof in one direction only in each of the limiting positions of the oscillating frame.

3. Apparatus for transfusion of blood comprising, in combination, a fixed frame, a three way valve plug and a cylinder having communication with the plug and both mounted on the fixed frame, an oscillating frame mounted for limited oscillation on the fixed frame and having a valve casing provided with three outlets, a reciprocating frame reciprocatingly mounted on the second frame and having a handle and a plunger for said cylinder, locking and unlocking detent mechanism interposed between the fixed frame and the other two frames and adapted to permit free reciprocation of the reciprocating frame in middle position of the oscillating frame and to afford full stroke reciprocation thereof in one direction only in each of the limiting positions of the oscillating frame, and integrating mechanism between the fixed frame and the reciprocating frame and adapted for actuation by movement of the reciprocating frame in one direction only.

4. Apparatus for transfusion of blood comprising, in combination, a fixed frame, a three way valve plug and a cylinder having communication with the plug and both mounted on the fixed frame, an oscillating frame mounted for limited oscillation on the fixed frame and having a valve casing provided with three outlets, a reciprocating frame reciprocatingly mounted on the second frame and having a handle and a plunger for said cylinder, a rack on the fixed frame, a yoke carried on the reciprocating frame and adapted to clear the rack at each end of the stroke thereof to permit turning of the oscillating frame, said yoke provided with notches

for the free passage of the rack, and detents on the yoke cooperating with the rack to insure full strokes of the oscillating frame.

5. In apparatus for the transfusion of blood a fixed frame having two standards each provided with an opening, a reciprocating frame, a plunger and a cylinder both removable through an opening in one standard, a pivotal yoke mounted on the reciprocating frame and having a movable claw for engaging and disengaging the rod of the plunger, a plug valve fitting removably mounted in an opening in the other standard, and a detachable coupling between the cylinder and plug valve fitting.
